UNITED STATES PATENT OFFICE.

AMBROSE J. B. BERGER, OF PHILADELPHIA, PENNSYLVANIA, ASSIGNOR TO
JAMES M. DODGE, OF SAME PLACE.

CHAIN CONVEYER FOR HANDLING COAL.

SPECIFICATION forming part of Letters Patent No. 391,223, dated October 16, 1888.

Application filed December 22, 1887. Serial No. 258,619. (No model.)

To all whom it may concern:

Be it known that I, AMBROSE J. B. BERGER, of Philadelphia, in the county of Philadelphia and State of Pennsylvania, have invented a new and useful Improvement in Chain Conveyers for Handling Coal, &c.; and I do hereby declare that the following is a full, clear, and exact description thereof, reference being had to the accompanying drawings, making part 10 of this application.

My invention relates to a new and useful improvement in that type or class of chain-conveyers in which a conveyer-chain with projecting flights is combined with some sort of 15 carrier-trough within which the flights travel and on the floor of which rests the material to be scraped or carried along by said flights, and more particularly to that species of this chain conveyer in which the conveyer-trough 20 and conveyer-chain are translated from a horizontal into an obliquely ascending direction for the purpose of carrying or conveying the coal or other material from a given level of supply or feed to some elevated destination.

In this type and species of chain conveyer serious difficulty has often been encountered by reason of the liability of pieces of the material getting wedged between the lower or working edges of the flights of the conveyer-chain 30 and the floor or bottom of the box or trough of the conveyer at the locality or localities at which the conveyer-chain passes beneath and partially around the periphery of the chain-wheel or chain-wheels over which the conveyer-chain travels; and to partially overcome 35 or avoid the evil consequences of the presence of any particles or pieces of material between the working-edges of the flights and the bottom of the conveyer-trough it has heretofore

been customary to mount the chain-wheel or chain-wheels just above referred to in slightly yielding boxes, so that said wheel or wheels, under the circumstances just mentioned, will be free to rise slightly to prevent any breakage 45 of the parts by reason of any such clogging by the material being conveyed. This arrangement of the wheel or wheels, however, has only partially overcome the difficulty alluded to, and as a partial remedy for such difficulty 50 it possesses an inherent disadvantage with reference to the chain-wheel which may be lo-

cated at the point where the direction of the conveyer-chain is translated from a horizontal to an obliquely ascending one, since the draft strain on the ascending portion of the conveyer-chain tends of course to lift said chain-wheel and any elevation occasioned by this natural tendency operates to lift the working-edges of the flights slightly away from the floor of the conveyer-trough at this point and 55 to thus permit the accidental passage and lodgment beneath the flights, while lifted, of particles of material being conveyed, which leads to serious difficulty.

I propose by my invention to provide for 65 use a chain conveyer of the type alluded to in which there will be no liability practically of any lodgment or passage of the material being conveyed between the lower or working edges of the flights and the floor of the trough on 70 which said edges are designed to run; and to this main end and object my invention may be said to consist, essentially, in the combination, with the usual chain conveyer and wheels of this type of machine, (whether one or all of 75 the wheels be mounted adjustably or not,) of a trough formed or provided with elastic or yielding bottom portions at the vicinity of those portions of the chain conveyer which run over or in connection with the wheel or 80 wheels of the conveyer, all as will be herein-after more fully explained, and as will be more particularly pointed out and specifically defined in the claims of this specification.

To enable those skilled in the art to which 85 my improvement relates to make and use a chain conveyer embracing my invention, I will now proceed to more fully describe the latter, referring by letters to the accompanying drawings, which form a part of this specification, 90 and in which I have shown my invention carried out in that form of apparatus in which I have so far practically embodied it and successfully used it.

In the drawings, Figure 1 is a partial sectional elevation of a chain conveyer made according to my invention. Fig. 2 is an enlarged view, of a similar character, of a portion of the apparatus seen at Fig. 1, showing only one of the chain-wheels and that portion of the 95 conveyer-chain trough which embraces the novel feature of construction in the latter, and

drawn on a scale sufficiently large to better show the details of construction with reference to the yielding or movable trough-bottom. Fig. 3 is a partial top view of the same.

5 In the several figures the same parts will be found designated by the same letters of reference.

A and B are respectively two of the chain-wheels or sprocket-wheels, beneath and partially around which travels the chain or chain belt C, from which project, in the usual manner, the flights c, each of said wheels in the case shown having its axle mounted in upwardly-yielding boxes. As will be seen by reference to the drawings, the shaft a of the wheel B, for instance, is mounted in sliding boxes x, which yield vertically and upwardly against the tension of suitable springs, y, which springs are compressed, in the usual manner, 20 between the upper surfaces of the sliding boxes and the under sides of the ordinary cap-plates of the metallic box-frames z.

D is the box or trough of the conveyer, into which the material is supposed to be discharged or to enter, (at the locality marked E, or elsewhere,) and within which it is carried along by the flights c of the conveyer-chain in the direction indicated by the arrows and, as shown, from the horizontal portion of said 25 trough into and upwardly through the obliquely-ascending portion to any desired elevated destination or point of discharge. Instead of having this conveyer-trough made after the fashion followed in making it previous 30 to my invention I form or provide said trough, as shown, at those portions which lie some distance vertically beneath the wheels A and B with yielding or movable bottom portions, e and f, each of which is secured at one of its 35 edges to the floor of said trough, and is constructed or arranged, as clearly illustrated, so as to spring upwardly and tend to keep against the working-edges of the flights c as the latter pass around and beneath the wheels A and B, 40 and to follow up and keep in contact with the working-edges of such flights in the event of any elevation or lifting (from any cause whatever) of the said chain-wheels and the chain-conveyer running in connection with them. 45

50 In the case shown both of these wheels A and B are capable of a slight upward movement from their lowermost or normal position by reason of having their journal-boxes mounted movably in the box-frames or stands in the 55 usual manner of sliding journal-boxes; but, as will be presently explained, in carrying my invention into effect this yielding capacity of either one or both of the said wheels is not an indispensable element of the machine 60 herein shown and described.

As shown, the yielding portions e and f of the conveyer-trough floor or bottom are composed of sheet-metal pieces, each of which is secured at one end by bolts S to the permanent 65 or unyielding portion of the conveyer-trough bottom, and is arranged and acts like a spring

plate or bar, tending always to rise and assume a straight condition.

As will be readily understood, there is necessarily a greater tendency or opportunity for 70 particles of the material being conveyed to get wedged beneath the lower or working edges of the flights c at the portion E of the conveyer-trough when the material enters there than at any other point, since, in order to afford an opportunity for the reception or feeding in of the material at this locality, the floor 75 of the trough must necessarily run off divergently from the circle which marks the path of motion of the working-edges of the flights c, 80 as they travel into operative coaction with the trough D and its contents. Therefore, the principal function and effect of the yielding and spring-like portion f of the conveyer-trough with its tendency to assume a straight 85 condition are merely, first, to prevent, to the greatest possible degree, the passage of any lumps or particles of material beneath the working-edges of the flights c as they take hold 90 of the material conveyed in at the point E; 95 and, second, to prevent any damage by any particle which may possibly get wedged beneath the lower edge of a flight and the bottom of the trough, at this locality, by yielding downwardly under such circumstances and 100 thus affording an opportunity for the particles or lumps of material to pass along with the rest of the mass being conveyed beneath the chain-wheel B, (whether its axle-box be upwardly yielding or not,) beyond which point, 105 of course, (until the chain conveyer arrives at the locality of the wheel A,) the chain and its flights are free to rise (more or less) to accommodate the presence of any particles which may be traveling along with the rest of the 110 mass but located beneath the working edge or edges of any flight or flights. It is, however, deemed preferable to have the wheel B capable of a slight yielding upwardly bodily to further facilitate the passage along of any material which may have traveled beneath the 115 working edge of any flight or flights during the ingress of the material to the conveyer-trough. The yielding bottom piece, e, performs substantially the same function as that of f, 120 with reference to yielding downwardly to accommodate any particles of material that may be dislodged between its upper surface and the lower or working edges of the flights c, 125 whether the chain-wheel A be upwardly yielding bodily or not; but in the case of this wheel A being upwardly yielding, (which is the preferable way of arranging it,) then the yielding bottom piece, e, performs the additional function of following up or keeping close to the lower working-edges of the flights c whenever by undue draft strain of the ascending portion of the conveyer-chain the wheel A is lifted more or less, thus preventing any 130 passage backwardly by gravity and beneath the working-edge of any one of the flights of any particle or particles of the material being

forced upwardly within or carried along on the obliquely-ascending portion of the conveyer-trough D. This yielding bottom piece, e, therefore involves a somewhat different mode of operation from the one shown at f, and performs, in conjunction with the yielding wheel A, a function supplemental to any performed by the device f combined with the wheel B, since in the case of the latter wheel there is no tendency exerted by the draft strain of the conveyer-chain to lift said wheel from its lowermost or normal position.

Of course the precise details of construction as well as the sizes, proportions, and particular arrangement of all the parts of the novel conveyer-machine shown may be more or less modified or varied without departing from the spirit of my invention; and wishing it to be understood that the yielding bottom pieces, e and f, combined, as shown, respectively, with that one of the chain-wheels which the draft strain of the chain is liable to lift, (when said wheel is made bodily yielding upwardly,) and with the wheel B, which, if made upwardly yielding, is never lifted by the draft strain of the conveyer-chain, may be either separately or jointly used with corresponding results and advantages in each case.

What I claim as new, and desire to secure by Letters Patent, is—

1. In combination with the conveyer-chain

provided with suitable flights, the trough in which said flights travel, and the chain-wheel or chain-wheels, around which travels the said conveyer-chain, the yielding bottom piece, f, 35 the whole arranged and operating together in substantially the manner and for the purpose described.

2. In a chain conveyer having an ascending or obliquely arranged trough and conveyer-chain portion, the combination, with the said conveyer-chain and the chain-wheel A, located where the direction of travel of said chain changes from a horizontal to an obliquely ascending one, of a conveyer-trough provided 40 with the yielding and following-up device e, the whole arranged and operating together substantially as and for the purpose explained.

3. In combination with the upwardly-yielding chain-wheel A and a chain conveyer passing beneath the same in the manner shown, the conveyer-trough provided with the yielding bottom portion or follower, e, the whole arranged and operating together in the manner and for the purposes set forth. 55

In witness whereof I have hereunto set my hand this 23d day of November, 1887.

A. J. B. BERGER.

In presence of—

JAMES M. DODGE,
GEO. M. BAKER.
